UNITED STATES PATENT OFFICE.

JOSEPH W. BRENKERT AND KARL BRENKERT, OF HIGHLAND PARK, MICHIGAN.

BURNER OR CARBON HOLDER.

Application filed April 17, 1924. Serial No. 707,042.

This invention relates to a burner or carbon holder of that type used in connection with moving picture machines, spot and flood lights, lantern houses and other places where an electric current is supplied to sticks of carbon for producing an arc light. The sticks of carbon are in opposed relation and it is necessary that the same be adjusted from time to time in order to obtain a perfect arc.

Our invention aims to provide a burner of the above type that is characterized by the novel construction and adjusting mechanism which permits of carbon sticks being easily and accurately shifted relative to each other, the adjusting mechanism including means for simultaneously shifting the carbon sticks in a linear direction to or from each other; shifting one of the carbon sticks horizontally in a plane at a right angle to the vertical plane of the burner, and swinging the other carbon stick horizontally in an arc relative to the burner, these three adjustments permitting of the ends of the carbon sticks being placed in such juxtaposition as to insure a perfect operative relation for an electric arc.

Our burner includes numerous means over burners heretofore used and all of these means will be brought out as the construction is hereinafter described, by aid of the drawings, wherein—

Figure 1 is a side elevation of the burner; Fig. 2 is a bottom plan of the same; Fig. 3 is a front elevation of the burner; Fig. 4 is a vertical cross sectional view of the same; Fig. 5 is a top plan of the burner, and Fig. 6 is a horizontal sectional view of a portion of the burner.

In the drawing, 1 denotes a gear housing provided with tubular portions 2 in which are mounted guide rods 3 and 4. Assuming that the burner is used in a vertical position, the guide rod 4 extends upwardly and the guide rod 3 extends downwardly. In addition to the tubular portions 2 there are tubular guide-ways 5 and slidable in these guide-ways are rod like racks 6 and 7 normally confronting each other so that a pinion 8 may mesh with said racks for adjusting the same longitudinally of the housing 1. The pinion 8 is mounted on the shaft 9 journaled in the housing 1 and mounted on the outer end of the shaft is a universal joint 10 for an operating rod 11 provided

with a hand wheel 12. The housing 1 is cut away so that easy access may be had to the pinion 8 by removing a detachable cover plate 13.

Mounted on the upper end of the rack 6 is a support 14 provided with an arm 15 which is slidable on the upstanding guide rod 4 and said guide rod cooperates with the rod like rack 6 in maintaining the support 14 in a defined relation to the gear housing so that said support may be moved to a front gear housing without any wobbling or tilting action. Slidable in the support 14 are the laterally extending guide rods 16 and 17 of a bracket 18 which is movable to and from the support 14 at a right angle to the plane of the guide rod 4 and the rack 6.

Rotatably mounted in the support 14, parallel to the guide rods 16 and 17, is a feed screw 19 in screwthreaded engagement with the nut portion 20 of the bracket 18 and said feed screw has a head 21 retained in the support 14 to prevent longitudinal movement of the screw in the support and thus effect movement of the bracket 18 relative to said support. On the rear end of the screw 19 is a universal joint 22 provided with a rod 23 and hand wheel 24, these last three mentioned elements being similar to the elements 10, 11 and 12 previously described.

Attached to the bracket 18 by screws 25 or other fastening means is a T-arm 26 which is insulated from the bracket 18 by an insulating washer 27. The T-head of the arm 26 has a side extension 28 provided with screw hole clamps 29 and 30. The clamp 29 holds the bared end 31 of an electrical conductor and the clamp 30 holds the insulated casing or arm 32 of said electric conductor both clamps cooperating in properly supporting the electric conductor with the clamp 30 taking any stresses or strains off of the bared end 31 of the conductor incident to such connection.

Attached to the outer end of the arm 26 by screws 33 or other fastening means is the shank portion 34 of a stationary V-jaw 35 which has a lateral extension 36 for a pivoted adjustable jaw 37 which has one end confronting the jaw 35 and its opposite end normally engaged by a thumb screw 38 carried by the shank 34 of the stationary jaw 35. The jaws 35 and 37 are adapted to cooperate in holding a depending or upper carbon

39. If the carbon is too small to be held by engagement of the jaws 35 and 37, the jaw 35 may be provided with a V-insert 40 having a hook 41 on its upper end by which it may be detachably suspended in the jaw 35 from the upper end of said jaw to cooperate with the jaw 37 for engagement with a small carbon.

Thus far we have described means for raising and lowering the carbon 39 and shifting it horizontally in a plane at a right angle to the gear housing 1, the first adjustment being accomplished by rotating the handle rod 11 to actuate the pinion and rack, and the consequent adjustment being accomplished by rotating the handle rod 23 to actuate the feed screw 19.

Mounted on the lower end of the depending rack 7 is a support 42 having an arm 43 slideable on the depending guide rod 3 and said arm is provided with a bearing 44 for a feed screw 45 provided with a universal joint 46 supporting a rod 47 and a hand wheel 48.

25 Pivottally mounted on the lower end of the rack 7 to laterally swing thereon is the bifurcated and apertured extension 49 of a bracket 50 provided with a socket 51 for the ball end 52 of the feed screw 45, said socket and ball establishing a universal connection between the bracket and feed screw which permits of the feed screw being adjusted to laterally swing the bracket 50.

Attached to the bracket 50 by screws 53 or other fastening means is an insulated T-arm 54 provided with an electric conductor 55 and clamping means 56 for a lower carbon 57, said clamping means and the manner of supporting the electric conductor 55 being similar to the like equipment for the upper carbon 39.

It is now apparent that when the upper carbon 39 is raised and lowered by virtue of the hand rod 11 that the lower carbon 57 is also shifted vertically, and in addition to this simultaneous adjustment of the carbons the lower carbon 57 may be swung horizontally in an arc relative to the rack 7 by manipulation of the rod 47. The T-arms 26 and 54 are safely insulated relative to the supporting brackets thereof and consequently the rods 11, 23 and 47 may be safely manipulated for adjusting the carbons 39 and 57.

55 We desire to direct attention to a few features of our burner which are not found in other burners and have proven advantageous in this class of burners. First, on account of the burners being subjected to heat when in operation there is expansion and when the burners cease to operate there is contraction, consequently the adjustable parts of the burner cannot be as accurately fitted as though contraction and expansion did not exist to an appreciable degree. If a

burner simply has a rack and pinion adjustment, without our guide rods 3 and 4, there is a very loose construction which prevents any degree of accuracy in properly positioning carbons, but by using our guide rods 3 and 4 stability is insured in connection with the rack and pinion mechanism, so that carbons may be raised and lowered and proper alignment maintained. Second, we attach considerable importance to the manner of holding the lower bracket 50. See Fig. 2. There is the extension 49 carried by the lower end of the rack 7 and the ball and socket connection which is some distance from the rack. In consequence of this arrangement there is a wide bearing point for the bracket and the T-arm 54. The two-point bearing across the rack permits of loose fitting of the parts without lost motion in the lower carbon supporting arm, and as brought out in the beginning such loose fitting is necessary to permit of easy movement of the adjustable parts when the burner is in operation and parts expanded due to heat. The same idea of a wide bearing is carried out in connection with the upper carbon and combining the advantages of these wide bearings with that gained by the guide rods 3 and 4, there is a very substantial structure that permits of adjustments being easily made to properly position the carbons. Further, we desire to direct attention to the carbon holders which have adjusting screws outside of the T-arms 26 and 54 where the screws may be easily manipulated, and by virtue of the adjustable jaws engaging the front sides of the carbons it is obvious that carbons, of various diameters can be correctly positioned. This is not possible where the clamping jaws have a side clamping action on carbons, for the reason that any difference in the diameter of the carbons will place one carbon out of alignment with the other. With our construction it is possible to maintain the light source in the center of the lens and this is a distinct advantage compared to carbons that are otherwise held.

Any suitable means may be employed for supporting the burner in a lamp housing or other structure and while in the drawings there are illustrated a preferred embodiment of our invention, it is to be understood that the structural elements are susceptible to such variations and modifications as fall within the scope of the appended claims.

What we claim is:—

1. A burner of the type described, comprising a gear housing, guide rods carried thereby, racks slideable in said housing, a pinion in said housing adapted for simultaneously shifting said racks, supports on said racks and slideable on said guide rods, brackets supported from said supports, carbon holders supported from said bracket, a screw

on one of said supports having a universal connection with the carbon holder of said bracket adapted to swing said bracket in an arc, and a screw and nut arrangement on the other support adapted to shift the bracket thereof away from said support.

2. In an arc lamp mechanism, an adjustable support, a laterally swingable bracket pivotally connected to said support, means

independent of the said support having universal connection with said bracket for adjusting said bracket, and a carbon holder carried by said bracket. 10

In testimony whereof we affix our signatures.

JOSEPH W. BRENKERT.
KARL BRENKERT.
